BY

Frederick S. Glancey, ATTORNEY.

UNITED STATES PATENT OFFICE.

HENRY L. GRASMUK, OF NEWARK, NEW JERSEY.

DESIGN FOR A LORGNETTE-CASE.

SPECIFICATION forming part of Design No. 35,293, dated November 19, 1901.

Application filed October 28, 1901. Serial No. 80,344. Term of patent 7 years.

To all whom it may concern:

Be it known that I, HENRY L. GRASMUK, a citizen of the United States, residing in Newark, county of Essex, and State of New Jersey, have invented and produced a new and original Design for a Lorgnette-Case, of which the following is a specification, reference being had to the drawings accompanying and forming a part of the same.

10 Figure 1 is an elevation of the front of the lorgnette-case. Fig. 2 is an elevation of the back of the lorgnette-case. Fig. 3 is a transverse section taken on line 3 3 of Fig. 1. Fig. 4 is a transverse section taken on line 4 4 of Fig. 2. Fig. 5 is a transverse section taken 15 on line 5 5 of Figs. 1 and 2.

The body A of the front of the case has a general cordate form and is joined to the elongated handle B, having incurved edges, as indicated, and to the calyx-shaped head C. It will be noted that indentations occur at the juncture of the handle and body and also at the juncture of the head and body. At the lower end of the handle the conventional leaf 25 elements, which form the border of the case and which have a general wavy curved form,

are curved inward to form a trefoil element at the point D. The ring E is attached to the end of the handle.

A cluster of daisies is used to ornament the 30 front of the lorgnette-case, the stems rising from the upper part F of the handle and the daisies covering the upper end of the handle and the lower part G of the body of the case. Daisies are also used at the juncture K of the 35 head and body. The front of the case has upon the central panel of the body of the case, as is indicated in Fig. 1, the female head H, with flowing hair, shown in profile.

The back of the case (shown in Fig. 2) is 40 formed exactly like the front, with the exception that the head is omitted from the central panel, so that an open central panel I, of irregular shape, is formed on the body of the case. 45

What is claimed as new is—

The design for a lorgnette-case, substantially as shown and described.

HENRY L. GRASMUK.
